UNITED STATES PATENT OFFICE.

JOSEPH A. SCHANNO, OF BROOKLYN, NEW YORK.

APPARATUS FOR REMOVING CYLINDER-LININGS.

1,315,865.

Specification of Letters Patent.

Patented Sept. 9, 1919.

Application filed November 20, 1918. Serial No. 263,405.

To all whom it may concern:

Be it known that I, JOSEPH A. SCHANNO, a citizen of the United States, residing at Brooklyn, in the county of Kings and State 5 of New York, have invented new and useful Improvements in Apparatus for Removing Cylinder-Linings, of which the following is a specification.

This invention relates to improvements 10 in apparatus for removing the linings of cylinders and has particular application to an apparatus for facilitating the removal of the linings of marine pump cylinders.

As is well known, owing to the unusual 15 corrosion, caused by galvanic action, salt and various impurities, marine pumps are usually built of iron with brass linings, and it is often necessary to renew the linings of the pumps. In carrying out the present invention, it is my purpose to provide an apparatus whereby the linings of the marine 20 pumps may be quickly and conveniently removed from the cylinder whenever necessary so that a new lining may be inserted in the 25 cylinder in place of the old lining.

It is also my purpose to provide an apparatus of the class described which may be easily and conveniently placed within the 30 pump cylinder and which may be operated within the pump cylinder in such manner as to quickly cut the lining of the cylinder so that such lining may be withdrawn from the cylinder and a new lining substituted therefor.

With the above recited objects in view and others of a similar nature the invention resides in the construction, combination and arrangement of parts set forth in and falling within the scope of the appended claims.

In the accompanying drawings:—

Figure 1 is a view in front elevation of a cutting device constructed in accordance with my invention.

Fig. 2 is a vertical sectional view through 45 the same.

Fig. 3 is a cross sectional view therethrough, the cutting apparatus being shown as mounted within a cylinder and acting upon the lining thereof.

Fig. 4 is a top plan view of the apparatus removed from the cylinder.

Fig. 5 is a similar view showing my improved cutting apparatus as used to cut a keyway in a shaft.

Fig. 6 is a view similar to Fig. 5 showing the device used for cutting a keyway in a hub of a gear or the like.

Fig. 7 is a fragmentary sectional view showing a portion of the reversing gear.

Fig. 8 is a cross sectional view of the same.

Referring now to the drawings in detail 1 designates an outer vertical casing which, in the present instance, is substantially U-shaped in cross section. Formed on the inner surfaces of the sides of the casing 1 at the open end or side of such casing are vertical flanges 2 extending toward each other. The top and bottom ends of the casing 1 are closed by means of plates shaped to conform to the cross sectional configuration of the casing 1. Mounted within the casing 1 is a guide casing 3 of cross sectional configuration corresponding to that of the casing 1 and having its side and top and bottom walls in engagement with the corresponding walls of the casing 1 and its open side and back spaced apart from the open side and back respectively of the casing 1 so that the guide casing may be shifted forward and backward within the casing 1 whenever desired or necessary for a purpose which will presently appear. In the present instance, the outer surface of the back of the guide casing 3 is formed with wedge 70 shoes 4 spaced apart vertically and the outer edges of the sides of the guide casing at the open front of such casing are formed with wedge shoes 5 spaced apart vertically and arranged in confronting relation with the flanges 2 on the casing 1. The numeral 6 designates wedge blocks, which, in the present instance, are interposed, respectively, between the wedge shoes 4 and the back wall of the casing 1 and the wedge shoes 5 and the flanges 2. When the wedge blocks in the front edges of the casing 3 are moved in one direction and the wedge blocks in the rear of the casing 3 are moved in the opposite direction, the casing 3 is shifted from the front toward the back of the casing 1, while when the direction of movement of the wedges is reversed, the guide casing is shifted toward the front or open side of the casing 1. These wedge blocks and wedge shoes 75 80 85 90 95 100 105

constitute a shifting means for the guide casing 3 and in this connection I wish it to be understood that other shifting means,

than that shown, may be employed without departing from the spirit of my invention.

Extending through the inner guide casing 3 and journaled in the top and bottom walls 5 in the casings 1 and 3 is a shaft 7 formed with a worm or screw thread 8 extending longitudinally thereof. Surrounding the shaft 7 and engaged by the screw threads 8 is a carriage 9 which, in the present instance, 10 is in the form of a sleeve having a flat side 10 formed with an outstanding ledge 11. Mounted upon the ledge 11 is a tool post 12 of some suitable construction and arranged within the tool post 12 is a cutter 13.

15 In the present instance, the lower end of the tool post 12 is pivotally mounted upon the ledge 11, as clearly shown in Fig. 2 of the drawing, so that the cutter will be held in engagement with the work while the carriage 20 is traveling in one direction under the action of the screw, and permitted to swing away from the work when the direction of movement of the carriage is reversed, thereby enabling the cutter to be returned to its 25 initial cutting position for a new operation.

The upper end of the shaft 7 is formed with a tang 14 that is equipped with any other means whereby said shaft may be connected up with a source of power such, for 30 instance, as an electric motor, or an air motor.

In practice, the apparatus just described is placed in the cylinder of the pump and the shaft 7 revolved. In the rotation of the 35 shaft 7 the carriage 9 is carried from one end of the cylinder to the other and the cutter 13 cuts the lining so that the latter may be removed from the cylinder.

By means of the wedge blocks and wedge 40 shoes, the guide casing 3 may be adjusted within the casing 1 so that the cutter may be moved into and out of engagement with the lining as is readily apparent.

In order that the casing 3 may be freely 45 shifted within the casing 1, the openings in the end walls of the casing 1 through which the ends of the shaft 7 extend are elongated thereby permitting free movement of the shaft in the shifting of the casing 3.

50 In this embodiment of my invention I have shown an appropriate form of reversing gear 15 which is connected with the outer end of the shaft 7 whereby the shaft may be reversed to reverse the direction of 55 movement of the carriage.

In the present instance the reversing gear embodies a stub shaft 16 integral with and projecting upwardly from the inner casing 3 and forms adjacent to its upper end, a 60 circumferential groove 17. In the present groove is a split collar 18. Rotatably mounted upon the stub shaft 16 is a sleeve like shaft 19 having its upper end formed with a tang 20. On the inner end of the 65 sleeve like shaft 19 is a spur gear 21 which

meshes with a similar gear 22 fast upon the shaft 7. By means of this construction it will be seen that the flexible shaft or other driving element that connects with the source of power may be connected with the tang 14 when it is desired to rotate the shaft 7 in one direction, while such driving element may be disconnected from the tang 14 and connected with the tang 20 when it is desired to rotate the shaft 7 in the reverse direction.

In Figs. 5 and 6 of the drawings I have shown my improved cutting apparatus as employed for cutting keyways in shafting and in gear hubs and in order that my apparatus may be used accurately in this work, the outer edges of the casing 1 are formed with longitudinally extending V-shaped ribs 24 as shown in the drawings.

While I have herein shown and described 85 one particular form of my invention by way of illustration I wish it to be understood that I do not limit or confine myself to the precise details of construction herein described and delineated as modifications and variations may be made within the scope of the claims and without departing from the spirit of the invention.

One of the variations which I have in mind at this time is the elimination of the 95 described means for reversing the direction of motion of the shafts 7 and 16 respectively. It is described that the motor employed is shiftable from one of these shafts to the other in order that the direction of rotation 100 can be changed. The proposed suggestions in lieu thereof are the embodiment with the mechanism of any well known form of gear shifting means which can be controlled without the necessity of changing the normal position of the driving motor.

I claim:—

1. An apparatus of the class described, an outer casing, an inner casing within said outer casing capable of being shifted from 110 one side of said outer casing to the other side, a carriage within said inner casing and capable of longitudinal movement within said inner casing, means for moving said carriage longitudinally, and a cutter on said 115 carriage adapted to be moved into and out of engagement with the work according to the shifting of said inner casing.

2. An apparatus of the class described, an outer casing having an open side, an inner 120 casing within said outer casing and having an open side adjacent to the open side of the outer casing, means between said inner and outer casing whereby the open side of the inner casing may be moved toward and away 125 from the open side of the outer casing, a cutter within said inner casing adapted to be engaged with the work through the open sides of said casing and to be moved into and out of engagement with the work according 130

to the movement of said inner casing within said outer casing, and means for operating said cutter.

3. An apparatus of the class described, an outer casing having an open side, an inner casing within said outer casing and having an open side adjacent to the open side of the outer casing, means between said inner and outer casing whereby the open side of the inner casing may be moved toward and away from the open side of the outer casing, a cutter within said inner casing adapted to be engaged with the work through the open sides of said casing and to be moved into and out of engagement with the work according

to the movement of said inner casing within said outer casing, a carriage upon which said cutter is mounted and means for operating said carriage to render said cutter active.

4. In an apparatus of the class described, a casing capable of lateral shifting movement, a carriage within said casing capable of longitudinal movement therein, means for moving said carriage longitudinally, and a cutter on said carriage adapted to be moved into and out of engagement with the work according to the lateral movement of said casing.

In testimony whereof I affix my signature.

JOSEPH A. SCHANNO.
